UNITED STATES PATENT OFFICE.

CARL J. BAER, OF ST. LOUIS, MISSOURI.

BARGE.

Application filed April 7, 1924. Serial No. 704,864.

To all whom it may concern:

Be it known that I, CARL J. BAER, a citizen of the United States, residing at St. Louis, in the State of Missouri, have invented certain new and useful Improvements in Barges; and I do hereby declare the following to be a full, clear, and exact description of the invention, such as will enable others skilled in the art to which it appertains to make and use the same.

The invention relates to a novel construction of boat of the barge or scow type, adapted particularly for the transportation of freight and commodities of all kinds on waterways generally, but more especially on inland waters subject to tidal currents, or constantly flowing currents, which vary in depth from shallow feeder streams to deep rivers, bays and open roadsteads, and has for its object to provide a barge or scow of knock-down type, in which the several elements constituting the hull and the sides and ends of the superstructure or housing are formed as separate units, preferably 25 pontoon-like members, adapted to be employed as separate floating transportation units, the elements of the superstructure being hingedly and removably connected to the deck of the hull, to assume an upright 30 relation normal to the deck, or to be folded onto the deck, in knock-down formation, to facilitate the loading, transportation and unloading of certain obvious classes of freight, and also to facilitate the disposition of the 35 barges in stacked relation when operating with no deck loads, thereby reducing the extent of the wetted surfaces and skin friction, and correspondingly reducing the power necessary to tow or propel a fleet 40 of such barges, particularly against a countercurrent, and also permitting a material increase in the speed of the entire load or equipment with a given towing or propelling power. The particular construction of barge 45 also admits of a relatively large number of unit barges being loaded in stacked relation and in knock-down form onto a mother boat or barge, of larger capacity, to permit all of the barges to be moved from place 50 to place at the normal speed of the mother boat or the towing or propelling power boat, thereby materially decreasing the time of operation and eliminating the dangers and difficulties of navigation incident to operating 55 the barges in strings or raft formation.

Each unit barge is preferably provided

with an undercut or scow type bow and a stern section inclined downwardly and rearwardly from the plane of the deck to facilitate the hauling or skidding of the units into stacked relation and, conversely, to permit the ready launching and flotation of the several stacked units, as the case may be. Preferably each unit barge is provided with a removable top or roof for the superstructure, constructed and applied in separable sections which, when not in use, may be stowed in nested or stacked relation in a hold, or compartment in the hull.

It is also desirable to provide each unit 70 with suitable coupling devices and dead-heading or vestibule forming plates, to admit of multiple barges being operated in string or series formation, or a series of parallel strings in raft-like relation, the cooperating 75 plates of successive barges serving to trap the water between the barges and thereby substantially eliminate the head resistance and the drag of the intermediate barges due to the displacement of the water by the bows 80 and sterns, respectively.

These and other structural and operative advantages of the invention will be more particularly set forth in the following specification, reference being had to the annexed 85 drawings, in which:

Fig. 1 is a pictorial diagram of a string of barges with the superstructures raised, as for transporting loose material in bulk.

Fig. 2 is a similar view with the superstructures collapsed onto the decks.

Figs. 3 and 4 are diagrammatic side elevations illustrating the mode of stacking the barges one upon another.

Fig. 5 is a longitudinal sectional elevation 95 of one of the barges.

Fig. 6 is a transverse sectional elevation of the same.

Fig. 7 is a fragmentary transverse sectional elevation of a barge showing a side 100 of the superstructure folded or collapsed onto the deck.

Fig. 8 is a diagram, in plan, of a string of barges provided with couplings and dead-heading devices between successive units.

Fig. 9 is a fragmentary sectional plan on the line 9—9 of Fig. 5.

Fig. 10 is a perspective view of a single barge having a removable cover or roof structure applied to the superstructure.

Fig. 11 is a side elevation, partly in section, of the barge shown in Fig. 10.

Fig. 12 is a sectional end elevation of the same.

Fig. 13 is a fragmentary perspective of a typical roof or cover of corrugated sheet metal.

Fig. 14 is a partial transverse section of the roof or cover.

Fig. 15 is a diagrammatic plan of a series of barge units stowed on a mother boat or barge.

Fig. 16 is a fragmentary perspective view illustrating the mode of coupling two barges.

Fig. 17 is a fragmentary side elevation, partly in section, of two coupled barges.

Fig. 18 is a fragmentary sectional elevation of the stern of a barge with the coupling unit collapsed in stowed relation.

Fig. 19 is a fragmentary plan view illustrating an application of a coupling means.

In a copending application Serial No. 693,134, filed February 11, 1924, there is described a construction and a system of unit barges and accessories, designed particularly for transporting freight on inland waterways to conserve the greatest possible economy of time and expense, both in respect of the movement of the loaded barges and the return of empty or partially loaded barges. The instant invention provides a type of barge adapted to be constructed in standard units of any desired size or capacity, capable of operating in all waters in which flotation is possible, under the same conditions and to the desirable ends and objects as set forth in said copending application, the present barge, however, presenting the additional advantages of being adapted to operation, either singly or in strings or rafts in rough open waters and also being convertible, individually, into a series of pontoon-like units, each capable of being operated in small streams to collect or discharge freight at points which would be inaccessible to the barge as a whole, and which is also susceptible of expeditious conversion into a flat or lighter type, a gondola type having an open top superstructure, or a box type having the superstructure on the hull or deck provided with an effective roof or covering, the three types being designed particularly for the accommodation of various kinds of freight.

Referring to Figs. 5 to 14 of the drawings, the construction and arrangement of the various elements of the novel barge will be described. The hull 1 is preferably constructed of fabricated metal sections in the form of sheets, bars, beams and the like, the general body formation of the hull being substantially rectangular in its several dimensions to define one or more holds, compartments or water tight sections capable of receiving liquid or solid freight in bulk; the bottoms, sides, ends and decks portion of the hull being suitably connected and re-

inforced, as good engineering practice may dictate. The hull is preferably provided with a scow type of bow 2 and with a semi-scow type of stern 3, the upper surface of which is sloped downwardly and rearwardly to constitute a declining extension of the deck for purposes to be hereinafter explained.

Disposed in substantially rectangular arrangement on the flat deck of the hull are the side members 4-4 and the end members 6 and 6' of a superstructure, which members, when in raised position, constitute the box-like housing for the reception of freight in bulk, said members, when laid flat on the surface of the deck presenting a substantially flat surface, parallel with the deck upon which relatively large units of freight, which may not be conveniently or economically stowed within the housing, may be carried. Each of the elements of the superstructure, to wit, the sides 4 and the end sections 6 and 6' are preferably constructed as hollow floatable units, formed of sheet metal, or other suitable material, connected, braced and reinforced by appropriate fabricated metal sections. Each element of the superstructure is preferably connected to the hull by suitable hinge-joints, such as 5, applied between the inner wall of the sides 4 and the deck 7 of the hull, 7 connecting the outer wall of the forward section 6 with the deck and 7' connecting the outer wall of the member 6' with the aft inclined section of the deck which connects with the stern. These hinge connections are preferably provided with removable pins to permit the bodily separation of the members of the superstructure from the hull, when the former are to be employed as individual units for transporting freight to and from the barge proper, under conditions where such operations may be found necessary or desirable, as for example in ferrying freight to and from the hull on shallow streams or other bodies of water inaccessible to the barge as a whole. A primary object of hingedly connecting the several members of the superstructure to the hull is to admit of the superstructure being collapsed onto the deck to provide a substantially flat surface for receiving certain types of freight, as hereinbefore explained, and alternatively, to enable the elements of the superstructure to be swung back into upright position on the deck to constitute the box-like housing aforesaid, the hinge connection serving to retain the several elements in fixed relation, so that, when the side and end sections are swung on their hinges to vertical position, the end walls of the side sections will abut the inner faces of the end sections as illustrated in Figs. 5 and 10.

In order to retain the members of the superstructure in properly adjusted rela-

tion to form the housing, the side sections 4—4 are preferably connected by cross braces 20—20 provided with turn buckles 21, by means of which the bottoms of the side sections 5 may be forced into firm engagement with the deck and the side sections properly spaced throughout. Each of the end sections 6 and 6' is preferably connected with the deck by a buck-stay 22 provided with a turn 10 buckle or other adjusting device, by means of which the footing or bottoms of the end sections may be drawn into firm engagement with the deck surface and the inner faces of the end sections be forced into proper 15 contacting engagement with the vertical ends of the side sections.

Preferably the joints between the bottoms of the superstructure sections and the deck, when the superstructure is in raised position, 20 are rendered water-tight by the provision of suitable packings, such as gaskets or rubber or the like 10 inserted in a groove 9 formed in the deck, said groove extending entirely around the deck in rectangular arrangement and preferably underlying the mid sections of the bottoms of the several members of the superstructure. Similarly, 25 water-tight joints are formed between the abutting vertical walls of the superstructure by packing gaskets, such as 15, disposed in grooves 14 in the end walls of the end sections 6 and 6' as exemplified in Fig. 9.

The forward end section 6 is adapted to be folded or collapsed forwardly onto the 30 deck, as indicated in dotted lines in Figs. 5 and 11, and the upper portion of this section is so constructed as to conform to and constitute an upward extension or projection of the scow-like bow of the hull, when said 35 section 6 is in its flat or collapsed position. The rear section 6' of the superstructure has its lower wall formed on a bevel or incline to correspond with the inclination of the rear section of the deck to constitute a firm 40 footing for the said section 6' when in upright position. This end section 6' is adapted to be folded outwardly and rearwardly of the hull and to lie flat along the rear inclination of the deck at the stern, as illustrated in Fig. 5 to afford an inclined skidway 45 over which another barge may be drawn onto the deck, where such superposed barge will rest upon the collapsed side members 4—4 and the front members 6 of the superstructure, these members occupying the relation on the deck of the barge as illustrated 50 graphically in Figs. 2 and 15.

In transporting certain types of freight, 55 it is obvious that provision must be made to protect the same from the elements and, to meet this condition, each unit barge is to be provided with a roof or cover for the superstructure, when the latter is raised to form the housing. This roof or cover may 60 take the form illustrated in Figs. 10 to 14,

inclusive, in which a series of sheets of corrugated metal, or other appropriate material, are so fashioned as to be disposed in overlapping relation to cover the entire open top of the superstructure. Each roof 70 section comprises a substantially flat body portion 25 having one edge bent downwardly to form an eave 26 and the other edge bent at an appropriate angle to constitute a hip or ridge 27. When the several sections are applied, the corrugations therein will intermesh throughout the overlap, and, by making the overlap sufficiently extensive, both in the transverse joints and in the ridge joints, water will be effectively 75 prevented from entering the housing through the roof, either in heavy rain storms or in rough water. In order to effectively support the roof or covering along the ridge line, a cable 30 is stretched between the highest points, at the mid sections, of the fore and aft superstructure members 6 and 6'. As an additional precaution to maintain the necessary rigidity 80 of the roof or covering, the cable is supported at various points in its length by means of struts 31 provided with socket members 32 to engage the cable, the lower ends of the struts being engaged in sockets 33 formed in or secured to the deck. Under 85 certain circumstances, it may be found advisable to supply an additional element of support to the roof or covering and, to this end, there is provided a cross beam 35, which, conveniently, may be made of angle iron, having flanges 37 on its ends which engage brackets 38 secured to the inner walls of the side members 4, as illustrated in Fig. 12. Secured to the middle of the cross beam 35 is a bracket or support 36 provided with a notch engaging cable 30 and holding the latter at a proper level and preventing sagging. The vertical flange of the cross beam 35 is tapered at its ends to conform to the slope of the roof sections 90 and affords an additional support for the roof at these areas of engagement therewith. Any suitable means may be employed for securing the roof in position, as for example ropes or cables 37 which run transversely over the roof and are secured to snatch blocks or similar quick fastening devices 38, which are preferably removably connected to the outer faces of the side walls 4. By this means, the roof may be held securely in position, but may nevertheless be quickly removed by casting loose the cables 37 and then lifting off the individual sections of the roof structure. 95

When the roof is not in use, the sheets 25 are assembled in nested or stacked relation and, together with the ridge supporting cable 30, the struts 31, the cross beam 35 and the binding cables 37, may be conveniently stowed in a hold 42 formed in the 100

forward part of the hull, to which access may be had through a hatchway 40 in the open forward deck, which hatchway is closed by a water-tight hatch cover 41.

5 As matters of economy of construction, maintenance and operation, the barges will preferably be constructed as standard units of relatively small size as compared with the very large, heavy and deep draft 10 barges commonly employed, so that the barges individually or in string or fleet formation may be operated with facility and expedition in the deeper waterways, while the separate barges, or the separate 15 elements of the superstructures, constituting individual pontoon-like elements may be operated in the shallower streams, both in collecting and delivering the freight, the elements of the superstructure being employed as ferries to and from the hull and 20 ultimately being reassembled on the hull when the barge is ready to rejoin the fleet.

When a series of the barges are to be 25 operated in string formation, they may, of course, be connected by the usual tow-lines with the towboat and with each other, when travelling with the current of a constantly flowing stream, thereby utilizing the force of the current as an assistance to navigation, 30 but ordinarily the barges will be coupled in close formation with dead-heading or vestibuling devices between the successive barges, as disclosed in my prior Patents Nos. 1,395,889 dated November 1, 1921; 35 1,400,787 dated December 20, 1921; 1,403,828 dated January 17, 1922; 1,406,602 dated February 14, 1922; and also in my copending application Serial No. 692,134, filed February 11, 1924. As explained in said 40 application, the material economy incident to the operation of the barges in string, or fleet formation, with the dead-heading devices between the barges to eliminate the head thrust and the stern drag of the individual barges, is especially effective in towing or propelling the barges against a counter-current and, obviously, barges constructed in accordance with the instant invention subserve all of the operable advantages as set forth in the application 45 aforesaid, with the additional advantage that, when the barges of a fleet, in whole or in part, are navigated light or with only partial loads, as for example when they 50 have a cargo of oil or other liquid in the holds of the hull and the hollow chambered members of the superstructure, one or more of the barges may be superposed on a sister barge, in a manner illustrated in Figures 55 3 and 4, thereby greatly reducing the wetted surfaces and the skin friction and correspondingly reducing the resistance to the movement of the stacked barges through the water. The stacking of the barges, one 60 upon another, is facilitated by the bow and

stern construction and the collapsible character of the superstructures. As indicated in Figs. 3 and 4, to effect the stacking, the superstructures of all subjacent barges are collapsed, the side members being folded 70 transversely onto the deck; the forward end member being folded on the forward portion of the deck, so that the upper side of said member constitutes a forward and upward extension of the bow, and the rear 75 member of the superstructure is folded onto the inclined rear portion of the deck at the stern. The sister scow to be stacked or superposed may then be skidded or hauled onto the first barge by a tow-line, or other suitable means, the operation being rendered comparatively easy of accomplishment by reason of the rake of the bow of the second barge and the inclined aft section of the 80 first barge. Each superposed barge is so disposed on the next subjacent barge that the bow sections are nested together with a forward overhang to constitute a substantially continuous bow of uniform rake, permitting the stacked barges to be operated 85 at the resultant deeper draft without materially increasing the head resistance. The number of barges which may be disposed in stacked relation will be limited, first, by the draft of the individual stacks, and the depth 90 of the water to be navigated, and, second, by the height of the stacks above the water level, which height should not be sufficient to render the stacks top-heavy. This stacking arrangement enables a relatively large 95 fleet of barges to be disposed in several stacks, the stacks either being disposed in string-like, or in raft-like formation, with the dead-heading devices of the barges, 100 which are submerged or partially submerged, being applied in operative relation to reduce the head resistance and the drag of the respective stacks, in the same manner 105 in which these resistances are eliminated when the barges are individually floated in fleet formation, as hereinbefore described. In order to break up the stack formation, 110 it is only necessary to reverse the operation, by launching the superposed barges successively over the stern of the subjacent barge, as for example by means of a line 115 from the power boat, or a windlass or other apparatus, to haul each barge rearwardly over the next barge below, until the first barge overhangs the stern of that below sufficiently to permit said first barge to slide 120 into the water. Obviously, in order to facilitate the stacking and unstacking relation, the contacting surfaces of the barges may be provided with rollers or straps in track-like formation to reduce the friction and prevent undue wear on the parts in contact. 125 The construction of the barges adapts them to be stowed in stacked relation on a mother boat or barge of larger size and 130

capacity, which mother boat may either constitute one of the towing or propelling units, or, if desired, may be a barge of the same general structural and operative character as the smaller units to be stowed thereon. In the particular exemplification of this mode of disposing and transporting the smaller unit barges, illustrated in Fig. 15, a mother boat 60 is a larger unit of the same type of the other unit barges, having a rearwardly and downwardly inclined stern to constitute a skidway over which the smaller unit barges are drawn to appropriate locations on the deck, the several smaller units being stacked one on the other and the several stacks disposed on the deck to effect a proper trim of the mother barge. It will be understood that the mother barge in this case may constitute a freight carrying unit, which may be included in the fleet and which is convertible into a carrier of a large number of smaller unit barges to permit of all of the elements of the fleet being assembled and returned to the ultimate point or points of delivery of the unit barges with a material saving of time and power, especially when the equipment is operated against a counter-current in the waterway. In case the mother boat constitutes one of the power units for towing or propelling the fleet, it may be constructed along the general lines, as disclosed in my application Serial No. 692,184, with ample capacity for receiving the smaller unit barges and stowing them in multiple stacked relation in lieu of the nested relation of the varying sized units disclosed in said co-pending application aforesaid.

The feasibility of operating the barges in stacked relation presents an additional advantage in navigating the barges in waterways that vary materially in depth or are obstructed by submerged bars. For example, in traversing a shallow tributary stream, the barges would be separately floated and towed. When the depth of the water is sufficient, the barges may be disposed in stacks of two and the number of barges in the respective stacks increased with the commensurate increase in the depth of the waterway. Should a row of stacked barges encounter a sand-bar or similar obstruction in the water-way, which bar was submerged sufficiently to permit a single barge to pass safely thereover, it would be necessary only to launch the several barges from stacked relation and float them separately over the bar and then reassemble them in stacked relation in the deeper water on the other side of the bar, a very advantageous method of lightering the stacked barge unit structure.

Because of the particular construction of the bow and stern of the unit barges, which enables them to be assembled one on another

in stacked relation, it is desirable that each barge be equipped with means for coupling it to the sister units fore and aft, so that all of the barges in a fleet or string will be securely connected, the coupling being so designed as to compensate for relative movement of the barges in all directions due to wave motion, and also to permit the assembled barges to be either drawn or pushed through the water by means of a leading power boat or a following power boat, or both. The coupling units must also be of such character that they will not interfere with the operation of stacking the barges and launching the barges from stacked relation. A typical form and arrangement of coupling between unit barges is illustrated in Figs. 16 to 19, inclusive. Referring to said figures, 60 indicates a stout post which is pivotally mounted in a bearing block 61 secured within the stern section of the hull and adapted to be swung to upright position through an opening in the inclined deck section of the stern, or, in the alternative, to be folded back into the compartment formed in the stern, as illustrated in Fig. 18. The post is supported in its upright position and securely braced, against movement in any direction, by tie rods or struts 65, which are connected to swivel bolts 66 secured within the hull and extending up through lateral openings in the stern section, the openings being of sufficient extent to permit the tie rods 65 to be dropped into the compartment in the stern when the coupling unit is collapsed. A coupler head 63 is connected to the upper portion of the post 60 by means of the swivel pin 64 which is journaled in a bearing 68 in the post, the connection between the coupler head and the post permitting the head to rotate freely on the horizontal axis represented by the swivel pin and thereby compensating for any relative rocking motion between the coupled barges. The coupler head 63 is provided with multiple jaws which are adapted to receive meshing jaws of a cooperating coupler block or head on a sister barge, the respective heads being provided with aligning openings to be engaged by the usual coupling pin 67.

The mating coupling unit is adapted to be removably applied to the bow of each barge and comprises a coupler block or head 70 having jaws meshing with the jaws of the coupler head 63 of a leading barge, said coupler head 70 being journaled on a horizontal pin 72 in the forked end 71 of a bar 73, which latter is adapted to be secured to the bow of the given barge by a pin 74 passed through an eye near the rear end of the bar 73 and engaging a socket in the mid section of the bow of the said barge. It will be noted that the connection of the coupler head 70 with the bar 73 by a hori-

zontally disposed pivot permits relative vertical movement, due to the waves, between the coupled barges, while the vertical pivotal connection between the bar 73 and the bow 5 of the following barge takes care of any relative lateral motion between the barges, the coupling members when connected nevertheless serving as a positive link between the barges, which will effectively transmit either 10 a pulling or a pushing force from one to the other and at the same time compensate for relative movement between the coupled barges in any direction.

Preferably, the bar elements 73 of the 15 couplings will be of sufficient length to separate the coupled barges at bow and stern sufficiently to prevent any overhang of the stern of a leading barge by the bow of a following barge, thereby avoiding possible 20 contact between the barges when the latter are rolling or pitching in rough water. It is to be understood, therefore, that the graphical illustration of the barges in overlapping relation at bow and stern does not indicate 25 the true relation of the barges, which, in actual practice, will be separated by considerable space, indicated by the broken section of the bar 73.

Neither of the coupling units as illustrated 30 and described, will interfere with the normal operation of collapsing the superstructures and stacking the barges one on another, for the reason that the coupling unit connected to the stern may be cast loose from the struts 35 65 and folded back into the compartment within the stern, while said struts may be swung on their pivotal connections with the hull and also dropped into the compartment, thereby leaving the aft inclined section of 40 the deck free to receive the rear end of the superstructure 6', as indicated in Fig. 18, and as hereinbefore described. The coupling member applied to the forward end of 45 the barge is readily removed from position by withdrawing the pin 74, which releases the entire coupling member, which latter may be stowed within the hull in the compartment provided for the stowage of the 50 roof sections.

55 What I claim is:

1. A boat of the scow or barge type comprising a hull and a superstructure including side and end sections adapted to be collapsed onto the deck of the hull, said hull and superstructure elements each constituting a 55 separate water-tight pontoon-like member.

2. A boat of the scow or barge type comprising a hull and a superstructure including side and end sections adapted to be collapsed onto the deck of the hull, said hull and superstructure elements each constituting a 60 separate enclosed pontoon-like member.

65 3. A boat of the scow or barge type comprising a decked hull and a superstructure including hollow walled side and end sec-

tions hinged to the deck and adapted to be collapsed onto the latter.

4. A boat of the scow or barge type comprising a decked hull having a scow bow and a downwardly and rearwardly inclined deck 70 section at the stern, and a superstructure including side and end sections, so hinged to the deck as to permit the side sections to be swung transversely onto the deck and the end sections to be swung forward and 75 aft onto the deck, respectively.

5. A boat of the scow or barge type comprising a decked hull, and a superstructure including side and end sections hinged to the deck and adapted to be collapsed onto the 80 latter, the upper portion of the forward end section having the form of an upward extension of the bow of the hull and the aft end section adapted to overlie the inclined stern section of the deck when said sections are 85 collapsed.

6. A boat of the scow or barge type comprising a decked hull and a superstructure including side and end sections hinged to the deck and adapted to be collapsed onto the 90 latter, the upper portion of the forward end section having the form of an upward extension of the bow of the hull and the aft end section adapted to overlie the inclined stern section of the deck when said sections 95 are collapsed, said aft end section constituting a skidway.

7. A boat of the scow or barge type comprising a decked hull, a box-like superstructure including side and end sections secured 100 to the deck and adapted to be folded or collapsed onto the deck, and means for effecting water-tight joints between the abutting portions of the respective sections and between said sections and the deck when the 105 superstructure is in raised position.

8. A boat of the scow or barge type comprising a decked hull, a box-like superstructure including side and end sections secured 110 to the deck and adapted to be folded or collapsed onto the deck, means for effecting water-tight joints between the abutting portions of the respective sections and between said sections and the deck when the superstructure is in raised position, and means for securing the side and end sections in upright and abutting relations.

9. A boat of the scow or barge type comprising a decked hull, a box-like superstructure including side and end sections secured 115 to the deck and adapted to be folded or collapsed onto the deck, means for effecting water-tight joints between the abutting portions of the respective sections and between said sections and the deck when the superstructure is in raised position, cross stays for locking the side sections in upright spaced relation and buck stays for locking the end sections in upright position and abutting 120 relation with the side sections.

10. A boat of the scow or barge type comprising a hull, a superstructure including side and end sections normally disposed in upright abutting relation to constitute a 5 housing and adapted to be collapsed onto the deck of the hull, and a removable roof or cover overlying and secured to said housing.
11. A boat of the scow or barge type comprising a hull, a superstructure including side and end sections normally disposed in upright abutting relation to constitute a 10 housing and adapted to be collapsed onto the deck of the hull, and a sectional and removable roof or cover overlying and secured 15 to said housing.
12. A boat of the scow or barge type comprising a hull, a superstructure including substantially rectangular side sections and 20 abutting end sections, the latter having cambered upper edges, all of said sections being so connected to the hull as to be collapsible onto the deck, a sectional roof or cover adapted to overlie the open top of the 25 superstructure, and removable means for supporting the roof amidship and longitudinally.
13. A boat of the scow or barge type comprising a hull, a superstructure including substantially rectangular side sections and 30 abutting end sections, the latter having cambered upper edges, all of said sections being so connected to the hull as to be collapsible onto the deck, a roof or cover including 35 sheet metal sections overlapping each other laterally and at the ridge line, and a longitudinal support extending along the ridge line and secured to the end sections.
14. A boat of the scow or barge type com-
- prising a hull, a superstructure including substantially rectangular side sections and abutting end sections, the latter having cambered upper edges, all of said sections being so connected to the hull as to be collapsible onto the deck, a roof or cover including 40 sheet metal sections overlapping each other laterally and at the ridge line, and a cable extending along the ridge line and secured to the end sections.
15. A boat of the scow or barge type comprising a hull, a superstructure including substantially rectangular side sections and abutting end sections, the latter having cambered upper edges, all of said sections being 45 so connected to the hull as to be collapsible onto the deck, a roof or cover including sheet metal sections overlapping each other laterally and at the ridge line, and a cable 50 extending along the ridge line and secured to the end sections, and struts disposed between the cable and the deck.
16. A boat of the scow or barge type comprising a hull, a superstructure including substantially rectangular side sections and abutting end sections, the latter having cambered upper edges, all of said sections being 55 so connected to the hull as to be collapsible onto the deck, a roof or cover including sheet metal sections overlapping each other laterally and at the ridge line, a cable 60 extending along the ridge line and secured to the end sections, and struts disposed between the cable and the deck said struts having a sliding engagement with the 65 cable and a socketed engagement with the 70 deck.
- 75

In testimony whereof I affix my signature.
CARL J. BAER.
